FOREIGN PATENT DOCUMENTS

JP 1583114 S 8/2017

Primary Examiner — Christy Nemeth*(74) Attorney, Agent, or Firm* — Leydig, Voit & Mayer,
Ltd.(57) **CLAIM**

The ornamental design for a charger, as shown and described.

DESCRIPTION

FIG. 1 is a front perspective view of the charger of the present invention;

FIG. 2 is a front view of thereof;

FIG. 3 is a rear view of thereof;

FIG. 4 is a top plan view of thereof;

FIG. 5 is a bottom plan view of thereof;

FIG. 6 is a right side view of thereof; and,

FIG. 7 is a left side view of thereof.

The broken lines show portions of the charger that form no part of the claimed design.
